US00D841327S

(12) United States Design Patent (10) Patent No.: US D841,327 S
(45) Date of Patent: * Feb. 26, 2019

(54) CONTAINER

(71) Applicant: L&F PLASTICS, CO., LTD., Miaoli County (TW)
(72) Inventor: Mu-Chuan Hsu, Miaoli County (TW)
(73) Assignee: L&F Plastics Co., Ltd., Miaoli County (TW)

() Term: 15 Years

(21) Appl. No.: 29/580,147

(22) Filed: Oct. 6, 2016

(30) Foreign Application Priority Data

Apr. 20, 2016 (TW) 105302126
Apr. 20, 2016 (TW) 105302126 D01
Apr. 20, 2016 (TW) 105302126 D02

(51) LOC (11) Cl. 03-01

(52) U.S. Cl. D3/297
USPC .....

(57) CLAIM

The ornamental design for the container, as shown and described.

DESCRIPTION

FIG. 1 is a perspective view of a first embodiment of a container showing my new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof;

FIG. 8 is a perspective view of a second embodiment of the container;

FIG. 9 is a front view thereof;

FIG. 10 is a rear view thereof;

FIG. 11 is a left view thereof;

FIG. 12 is a right view thereof;

FIG. 13 is a top plan view thereof; and,

FIG. 14 is a bottom plan view thereof.

The broken lines illustrate portions of the container that form no part of the claimed design.

1 Claim, 10 Drawing Sheets
